UNITED STATES PATENT OFFICE.

JOHN McLEOD, OF DOWNING, WISCONSIN.

BOAT.

Application filed July 6, 1923. Serial No. 649,910.

To all whom it may concern:

Be it known that I, JOHN McLEOD, a citizen of the United States, residing at Downing, in the county of Dunn and State of Wisconsin, have invented certain new and useful Improvements in Boats, of which the following is a specification, reference being had therein to the accompanying drawing.

This invention relates to boats and has special reference to small boats such as used for fishing, pleasure, or the like.

The principal object of the invention is to produce a novel form of boat having the maximum degree of safety.

Another object is that of simplicity of construction throughout the major portion of the boat.

Other objects and advantages of the invention will appear in the further description thereof.

Referring to the accompanying drawing forming part of this application and in which like reference characters indicate like parts:

Figure 1 is a longitudinal vertical central sectional view of a boat embodying my invention,

Figure 2 is a top plan view, and

Figure 3 is a transverse sectional view, somewhat enlarged, on the line 3—3, Figure 2.

The hull 1 of the boat intermediate of the after bulkhead 2 and the forward bulkhead 3 is circular in cross-section and of barrel-like construction, that is to say composed of a plurality of spaced circular hoops 4, upon which the outer wall, or boards if constructed of wood, are securely fastened. The bottom portion may be reinforced with a floor, as indicated at 5, or in any desired manner. Approximately one-sixth of the diameter of the hull inwardly of the sides thereof is installed a longitudinal bulkhead 6 it being secured to spaced fractional bulk-

head sections 7, that is to say there may be any desired number of fractional bulkhead sections upon either side of the hull, forming a plurality of air chambers intermediate of same and the bulkhead 6 and the skin of the hull.

In approximately the center of the upper

deck of the hull is formed the cock pit opening or hatch indicated at 8, it being surrounded by suitable coaming. Upon the cylindrical hull portion of the boat is formed the flat deck indicated at 9 having vertical side walls 10 extending downwardly approximately on a plane tangent with the side walls of the cylindrical portion, thus forming approximately triangularly shaped air spaces 11 upon the upper opposite corners of the hull and insuring a hull construction that can only remain right side up either on or under the water.

The bow 12 of the boat is of separate construction and made of any form desired preferably with an overlapping flange portion indicated at 13 which is securely riveted or bolted externally of the forward end of the hull 1. This bow section is designed to be air tight, forming a buoyant compartment for the forward end of the vessel. The after or stern end 14 is of like separate construction and may be attached to the stern of the hull in the same manner, it being provided with a tunnel or shaft tube 15 for reception of the propeller shaft, if the same be a power driven boat. This stern portion 14 is also of air tight construction forming a buoyant section at the stern of the boat.

From the foregoing it is evident that I have produced a form of boat construction the individual parts of which are uniform for a major portion of the structure, thus lessening the cost of construction, and one that when built would be exceedingly seaworthy and safe. While I consider the most practical form of such boat as being without a keel it is evident that if desired bilge keels may be employed one upon either side and thus in no way prevent the boat navigating successfully in shallow water.

Having thus described my invention, what I claim and desire to secure by Letters Patent, is:

A boat comprising in combination a main hull substantially tubular in form throughout, a transverse bulkhead at either end of said hull, a separable stern portion comprising an air tight chamber, a separable bow portion comprising an air tight chamber, cellular air chambers longitudinally of and

within either side of the main hull, a flat deck over the main hull having depending side and end walls attached to the walls of the hull forming longitudinal air chambers above the last mentioned air chambers, and a cockpit within the hull, substantially as described.

In testimony whereof I hereunto affix my signature in the presence of two witnesses.

JOHN McLEOD.
